UNITED STATES PATENT OFFICE.

GEORGE ANTHONY SINGERLY, OF PHILADELPHIA, PENNSYLVANIA.

DESIGN FOR A HORSESHOE.

SPECIFICATION forming part of Design No. 27,040, dated May 11, 1897.

Application filed April 1, 1897. Serial No. 630,307. Term of patent 14 years.

To all whom it may concern:

Be it known that I, GEORGE ANTHONY SINGERLY, a citizen of the United States, residing in the city and county of Philadelphia, State of Pennsylvania, have invented and produced a new and original Design for a Horseshoe, of which the following is a specification, reference being had to the accompanying drawings, forming part thereof.

10 The leading feature of my design for a horse or animal shoe is a shoe having on the tread thereof depending segmental rims extending around the toe and heel portions thereof and necks intermediate of said portions at the upper part of the shoe.

15 Figure 1 represents a bottom plan view of a horseshoe embodying my design. Fig. 2 represents a section of the shoe on line *x x*, Fig.

1, and an elevation of the relative inner side thereof.

A designates a horseshoe having on the tread thereof the depending segmental rims B B and C C, it being noticed that the rims B B occupy the toe portions of the shoe and the rims C occupy the heel portions thereof.

D designates necks on the upper portions of the sides of the shoe, the same being intermediate of the adjacent ends of the rims B and C.

What I claim is—
The design for a horseshoe substantially as described and shown.

GEORGE ANTHONY SINGERLY.
